United States Patent Office.

FREDERICK TOWNSEND, OF ALBANY, NEW YORK.

Letters Patent No. 95,955, dated October 19, 1869.

IMPROVEMENT IN STONE-CUTTING MACHINES.

The Schedule referred to in these Letters Patent and making part of the same

To all whom it may concern:

Be it known that I, FREDERICK TOWNSEND, of the city and county of Albany, in the State of New York, have invented an Improvement for Operating the Chisels of Stone-Quarrying Machinery; and I do hereby declare that the following is a full, clear, and exact description thereof, reference being had to the accompanying drawings, making part of this specification, in which—

Figure 1 is a side view of a rotary chisel-carrying head, having four chisels applied to it, and having a portion of its face-plate broken away.

This invention relates to an improvement on the stone-quarrying machine, for which I made application for Letters Patent of the United States on the 6th day of August, 1869.

My object is to prevent chisels or drills from dragging upon the stone after the blows have been given, by so applying the chisels to their rotary head that they will respectively continue the work immediately after the blows are struck, in the direction of the blows, and in the line of their axes, as will be herein-after explained.

To enable others skilled in the art to understand my invention, I will describe its construction and operation.

In the accompanying drawings—

A represents a circular chisel-carrying head, which consists of two circular disks, secured rigidly together, with chisel-guides b b confined between them.

This cam C is prevented from rotating with the head A, by securing it in any suitable manner to the frame upon which the shaft B has its bearings; and, as the head A is rotated, the said cam retracts the chisels successively, and at proper points releases them, and allows their springs to force them downward upon the stone, as will be hereinafter explained.

In my application for Letters Patent, referred to, the chisels were applied to their rotary head, so as to radiate from the axis thereof, which arrangement caused the chisels to drag upon the stone after every blow until they were moved around far enough to be lifted from the stone.

I now arrange the chisels tangent to a circle described within the circumference of the head A, so that the chisels are at right angles to each other if four are used, as shown by the drawing, or they may

be arranged in the form of a polygon if more than four chisels are used.

Each chisel E is applied between parallel guides b b, so as to have endwise motion, and around each chisel a spring, c, is coiled, one end of which acts against lug e, and the other end acts against a shoulder at the opposite end of a slot made through head A. Thus it will be seen that the operation of each spring c is to thrust outwardly its chisels, and give the blows.

Each chisel E is provided with a vibrating retracting arm, D, which is pivoted to the head A at a, and which has its free end fitted loosely into a recess made into the head of the chisel, and on that edge of each arm D, which is next the cam C, a toe, d, is formed, which is held against the periphery of said cam by the spring c of the chisel, acted upon by said arm D.

It will be seen, from the above description, that during the rotation of the head A, in the direction indicated by the arrow in the drawing, the chisels E will be successively retracted by the cam C and arms D, and that as the chisels successively arrive at the proper point in their revolution for striking the stone, the toes d will leave that point of the cam which has the greatest radius, and allow spring c to effect the blows by their recoil.

In practice the cam c will be adjustable around its shaft B, so that the chisels may be caused to strike at different angles with respect to the plane of the stone which is being channelled.

I do not claim broadly, under this petition, the use of the chisels which receive rotary and endwise motions, as this feature is described and claimed by me in my application for Letters Patent, filed August 6, 1869, above referred to; nor do I confine myself to the use of vibrating arms D, as media through which cam C operates to retract the chisels, as other means equivalent thereto may be employed in their stead.

Having described my invention,

What I claim as new, and desire to secure by Letters Patent, is—

The tangentially arranged chisels E, applied to a rotary head, and operated substantially as and for the purpose described.

Witnesses: FREDK. TOWNSEND.
